CIGARETTE FILTER

Sidney Van Tuyl, Fort Pierce, Fla.

Application June 6, 1956, Serial No. 589,604

5 Claims. (Cl. 131—208)

My invention relates to an improved cigarette filter and to a method of making the same and more particularly to a cigarette filter which provides filtering action while permitting smoke to be drawn through the filter with ease, and to a method for making the filter.

Many attempts have been made in the prior art to provide a cigarette filter which effectively filters cigarette smoke to remove a substantial amount of the tobacco tars and nicotine from smoke being inhaled. These filters of the prior art are formed of wads of fibrous material or from rolls of paper and other like materials. Where the filters of the prior art are sufficiently dense to give effective filtering action, they do not permit smoke to be drawn easily through the filter. For this reason, cigarettes provided with dense filters do not give a satisfactory smoke. Where the filters of the prior art are constructed to permit easy drawing, the filtering action is poor.

The most effective filter which permits ready passage of air or the like is that designed by nature. The hairs in the human nasal passages readily permit air to be drawn into the lungs while trapping harmful foreign matter. I have invented a cigarette filter which utilizes in part the principle embodied in the human nostril to permit ready drawing of smoke through the filter while provided effective filtering action. My filter is simple and inexpensive to manufacture. I have also invented a method for making my cigarette filter.

One object of my invention is to provide a cigarette filter which gives effective filtering action while permitting smoke to be drawn through the filter with relative ease.

Another object of my invention is to provide a cigarette filter which gives effective filtering action while being inexpensive to manufacture.

A further object of my invention is to provide a method of making my cigarette filter.

Other and further objects of my invention will appear from the following description.

In general my invention contemplates the provision of a cigarette filter including a pair of paper strips formed with sharp creases extending in a direction at an angle to the strip axes. Owing to the nature of the paper I employ, the sharp creases break and displace fibers along the crease edges, thus causing them to extend into the passages formed by the paper rolled upon itself. I place the strips of a pair one on the other with the creases of the respective strips relatively angularly disposed. The filter is formed by rolling the superposed strips to form a cylinder having a plurality of generally axially extending tortuous smoke passages into which the upstanding fibers extend. Smoke being drawn through the passages is filtered by the fibers upstanding from the creases to collect a large percentage of tobacco tars and nicotine contained in the cigarette smoke.

In the accompanying drawings which form part of the instant specification and which are to be read in con-

2

junction therewith and in which like reference numerals are used to indicate like parts in the various views:

Figure 1 is a perspective view of a cigarette including my filter.

Figure 2 is a plan view of one strip of a pair of paper strips of which my filter is formed.

Figure 3 is a plan view of the other strip of a pair of strips of which my filter is formed.

Figure 4 is a plan view of a pair of superposed strips 10 of which my filter is formed.

Figure 5 is a sectional view of the strip shown in Figure 2 taken along the line 5—5 and drawn on an enlarged scale.

Figure 6 is a perspective view of my filter.

Figure 7 is a fragmentary perspective view of a pair of filter forming strips in superposed relationship showing the path of smoke through my filter.

Figure 8 is a schematic view of one form of apparatus on which my filter may be constructed.

More particularly referring now to Figures 1 to 7 of the drawings, my filter, indicated generally by the reference character 10, may be assembled in a cigarette 12 in any convenient manner known to the art. For example, the filter may be encased in the paper jacket 14 of the cigarette. As can be seen by reference to Figure 2, my filter includes a first paper strip 16 formed with a plurality of sharp creases 18. These creases 18 extend at an angle A to the minor axis of the strip 16 which may be taken along the line x—x in Figure 2. As can be seen by reference to Figure 3, my filter includes a second paper strip 20 formed with a plurality of sharp creases 22 making an angle B with the minor axis of the paper strip 20, which may be taken along the line y—y of Figure 3.

I form strips 16 and 20 from a paper having a nature such that fibers 24 of the paper are broken or displaced so as to stand out from the edges of the creases 18 and 22. The paper of which strips 16 and 20 are formed is any paper which releases pulp or lint fibers from its bond when the paper is sharply creased. As will be explained hereinafter, the fibers 24 perform the actual filtering action of my filter.

Referring now to Figures 4 and 7, in the next step of forming my filter I superpose the strip 16 on the strip 20 with the creases 18 relatively angularly disposed with respect to the creases 22. While the angles A and B may be any convenient angles, preferably I make these angles 45°. With the strips 16 and 20 superposed, a plurality of diamond-shaped traps or pockets, indicated generally by the reference character 26, are formed. When cigarette smoke is drawn through my filter in the direction of the axes x—x and y—y of the strips, smoke passes through a succession of traps 26 along tortuous paths, one of which is indicated by the arrows in Figure 7. A great number of fibers 24 extend into each of the traps or pockets 26 in the path of smoke traveling through a pocket. The smoke is effectively filtered by these fibers 24 as it travels from one pocket 26 to a succeeding pocket. In the course of the passage of smoke between the paper strips 16 and 20 as shown in Figure 7, the fibers 24 adsorb and absorb a substantial amount of the tobacco tars and nicotine in the smoke. It will be appreciated that the paths provided by a succession of traps 26 permit smoke to be drawn through the filter with relative ease. At the same time, fibers 24 effectively filter the smoke.

In the final steps of making my filters, I cut the superposed strips 16 and 20 to the proper length and roll up the cut, superposed strips to form the filter. In its final configuration, the filter appears as is shown in Figure 6.

Referring now to Figure 8, I have shown one form

of apparatus on which my filters may be made. The strips 28 and 30 of a pair of filter-forming strips, of the type paper described hereinabove, pass through the tips of respective pairs of fluted rollers 32 and 34 and 36 and 38. Rollers 32 and 34 have fluted surfaces which mesh to crease strip 28 to provide it with creases, such as the creases 18, which make an angle A with a transverse axis of the strip. The pair of rollers 36 and 38 are fluted and mesh to provide strip 30 with creases similar to the creases 22, which make an angle B with a transverse axis of strip 30. Any convenient drive means known to the art may be employed to drive the fluted rollers in the directions of the arrows in Figure 8.

After emerging from the pairs of rollers 32, 34, 36 and 38, the creased strips 28 and 30 are fed to a pair of rollers 40 and 42 which bring the strips together in superposed relationship on a table 44. As the superposed strips advance across table 44, a knife 46, reciprocated in a housing 48 by any convenient means, such as a cam 50, cuts the superposed strips into predetermined lengths. After being cut, the superposed lengths are rolled by hand or by any convenient means known to the art to form filters 10 which may be assembled in cigarettes.

In use of my filter 10 it is assembled with a cigarette 12 with the strip axes x—x and y—y extending in the direction of the cigarette axis. Smoke being drawn from the cigarette through the filter travels along the tortuous paths, one of which is indicated in Figure 7, through successive traps or pockets 26. As the smoke travels from pocket to pocket, fibers 24 upstanding from the edges of creases 18 and 22 collect a relatively large percentage of the tobacco tars and nicotine present in the smoke. While providing this effective filtering action, my filter permits the smoke to pass readily through the filter.

In order to make my filter, I first form a pair of strips of paper with sharp creases extending in a direction at an angle to the strip axes. After having creased the strips, I assemble them in superposed relationship with their creases relatively angularly disposed. I cut the strips to length and roll them to form finished filters which may be assembled into cigarettes.

While I have shown and described my filter as including only two strips 16 and 20 of paper, it is to be understood that as many strips as are necessary or desired may be employed with adjacent strips having their creases relatively angularly disposed. Further, it is to be understood that for purposes of clarity in exposition the separation between adjacent creases 18 and adjacent creases 22 has been greatly exaggerated. In fact the creases are extremely sharp and close together.

It will be seen that I have accomplished the objects

of my invention. I have provided a cigarette filter which provides effective filtering action while permitting smoke to be drawn through the filter with relative ease. I have provided a method for making my filter. My filter is relatively inexpensive to manufacture.

It will be understood that certain features and sub-combinations are of utility and may be employed without reference to other features and sub-combinations. This is contemplated by and is within the scope of my claims. It is further obvious that various changes may be made in details within the scope of my claims without departing from the spirit of my invention. It is, therefore, to be understood that my invention is not to be limited to the specific details shown and described.

Having thus described my invention, what I claim is:

1. A filter for cigarettes including in combination a first strip of paper formed with sharp creases providing channels extending in a direction at an acute angle to the transverse axis of the strip and ridges separating said channels and a second strip of paper formed with sharp creases providing channels extending in a direction at an acute angle to the transverse axis of the second strip and ridges separating said channels, said strips being superposed with ridges of one strip contacting ridges of the other strip and with the channels of the respective strips extending in diverging directions to form a plurality of connected filter pockets providing labyrinth paths for smoke drawn through the filter, the channels of each of said strips extending in a direction making an acute angle with the longitudinal axis of the filter.

2. A filter as in claim 1 in which said creases provide edges and including a plurality of fibers extending outwardly from said crease edges.

3. A filter as in claim 1 in which said paper readily releases fibers from the paper bond when creased.

4. A filter as in claim 1 in which said first strip creases and said second strip creases extend at angles of 45° with respect to the strip axis.

5. A filter as in claim 1 in which the creases of the respective strips are disposed at right angles with respect to each other.
